US00D691496S

(12) **United States Design Patent**
Kazaoka

(10) **Patent No.:** **US D691,496 S**
(45) **Date of Patent:** **** Oct. 15, 2013**

(54) **RADIATION DETECTOR**

(71) Applicant: **Mitsubishi Heavy Industries, Ltd.**,
Tokyo (JP)

(72) Inventor: **Naoki Kazaoka**, Tokyo (JP)

(73) Assignee: **Mitsubishi Heavy Industries, Ltd.**,
Tokyo (JP)

(**) Term: **14 Years**

(21) Appl. No.: **29/453,384**

(22) Filed: **Apr. 29, 2013**

(30) **Foreign Application Priority Data**

Nov. 7, 2012 (JP) 2012-027222

(51) **LOC (9) Cl.** **10-04**
(52) **U.S. Cl.**

USPC **D10/47; D10/78**

(57) **CLAIM**

The ornamental design for a radiation detector, as shown and described.

DESCRIPTION

FIG. 1 is a perspective view of a radiation detector.

FIG. 2 is a perspective view thereof.

FIG. 3 is a front elevation view thereof. A rear elevation view is a mirror image of the front elevation view.

FIG. 4 is a top plan view thereof.

FIG. 5 is a bottom plan view thereof.

FIG. 6 is a left side elevation view thereof; and,

FIG. 7 is a right side elevation view thereof.

The oblique line shading illustrates translucency.
